(54) **PRINTING PRESS**

(76) Inventor: **Adam Ramage**

Adam Rammage of Philadelphia, Pennsylvania
Letters Patent.

The schedule referred to in these Letters Patent and making part of the same, containing a description of the words of the said Adam Rammage, himself, of his improvement in the Printing Press.

It is known that I Adam Rammage of the City and County of Philadelphia and State of Pennsylvania, have made an improvement in the Printing Press; which is described as follows.

The press consists of the frame, for containing and supporting the different parts of the press, the carriage on which the types or other objects to be impressed are placed; the ribs upon which the carriage is and out below the platin, the Platin for giving the impression, a vertical bar attached to the platin, and for pressing it down upon the types;— the spiral spring for raising the platin up again, and a lever with a swiv or toggle joint attached to one end and turning on guides, or a pin for working the press, placed on the top head of the press,

The frame which is made of wrought-iron is of any convenient size and strength adapted to the size of the Press— and is done in the shape that is the lower part of the cheeks, are straight and parallel; the sides of the upper parts incline inward; and the top joins the sides together, either in a straight line or a curve, at bar or plate of wrought iron, of suitable size and thickness extends from one cheek to the other, at or near the point where the cheeks make an angle or bend; through this bar or plate, passes the vertical bar, attached to the platin, also the iron pins fixed to the upper side of the platin by which it is so kept parallel while working. This the top or head of the frame is an opening which admits the passage of the vertical bar.

upon the upper end of which the power is applied, —
The vertical bar, attached to the platen, is also made of wrought iron & steel, is of size and strength adapted to the press; passing the horizontal plate, connecting the cheeks, and the head or top of the frame. Around this upright bar is a spiral screw, for raising the platen, one end of which rests upon the horizontal plate and the other is attached to a female screw, which turns on a screw cut on the vertical bar, and by which the spiral spring can be regulated, — At the end of the lever which works on god geons pr. Torsionally, is attached a segment of an elliptical or eccentric roller, on a toggle-joint working on the top of the vertical bar, and gives the pressure upon the platen and types &c.

Upon the top of this vertical bar, a small piece of steel is placed between the pressing power and top of the vertical bar, working in a channel. A regulating screw is so placed as to regulate the force to be given by the lever &c,

All the other parts of the press are too well known to need a further description. Operation The form or thing to be pressed, having been placed upon the carriage, is inked, and the white paper put upon the tympan and the frisket turned down. The carriage is then run in by the runner under the platen.

The pressman or operator then lays hold of the bar, and forces the eccentric roller or toggle joint down upon the head of the vertical bar, which forces the platen down upon the types &c, and gives the impression required.

The invention here claimed and desired to be secured by Letter, Patent, consists in the general construction of the before described press, with the arrangement of its several parts, so as to do away with many of the expensive parts of the common printing Press; and to produce one, which at the same time combines cheapness, power, and convenience. But what I particularly claim as my improvement is the wrought iron frame, which has the strength of a wrought ^{iron} bar, drawn through

This principle I claim, however applied in the printing of
and of whatever shape the head and checks may be made, or for
deal or copying pieces, &c.

For a further illustration of my invention and improvement
I refer to the model and drawing of the same deposited in the
Patent Office.

In testimony whereof I have subscribed my
name before two witnesses, this eighth day of November 1834.
